[57] CLAIM

The ornamental design for a footwear midsole, as shown.

DESCRIPTION

FIG. 1 is a left side elevational view of a footwear midsole showing our new design;
FIG. 2 is a top plan view thereof;
FIG. 3 is a front elevational view thereof;
FIG. 4 is a right side elevational view thereof;
FIG. 5 is a bottom plan view thereof;
FIG. 6 is a rear elevational view thereof;
FIG. 7 is a left side elevational view of an alternate embodiment of the design shown in FIG. 1;
FIG. 8 is a top plan view of FIG. 7;
FIG. 9 is a front elevational view of FIG. 7, the toe flap shown unsecured;
FIG. 10 is a right side elevational view of FIG. 7;
FIG. 11 is a bottom plan view of FIG. 7;
FIG. 12 is a rear elevational view of FIG. 7; and,
FIG. 13 is a bottom plan view of a second embodiment of the design shown in FIG. 1; the side elevational views shown in FIGS. 7 and 10, the front elevational view shown in FIG. 9, and the rear elevational view being substantially similar to FIG. 12 except for the aperture.
The broken line showing of a shoe upper in FIGS. 1 and 4 is for illustrative purposes only and forms no part of the claimed design.
